PAGE 2

FIG. 1 is a front perspective view of a portable adding machine showing my new design as it appears with the carrying handle in raised position.

FIG. 2 is a rear perspective view of the same, and

FIG. 3 is a top plan view thereof with parts of the carrying handle being shown broken away for convenience of illustration.

The essential features of my design reside in the portions shown in solid lines.

I claim:

The ornamental design for a portable adding machine, as shown and described.
